UNITED STATES PATENT OFFICE.

CHARLES P. COTTRELL, OF WESTERLY, RHODE ISLAND, ASSIGNOR, BY MESNE ASSIGNMENTS, TO C. B. COTTRELL & SONS COMPANY, OF NEW YORK, N. Y., A CORPORATION OF DELAWARE.

PRINTING MECHANISM.

1,130,259.

Specification of Letters Patent.

Patented Mar. 2, 1915.

Application filed June 27, 1911. Serial No. 635,621.

To all whom it may concern:

Be it known that I, CHARLES P. COTTRELL, a citizen of the United States, and resident of Westerly, in the county of Washington 5 and State of Rhode Island, have invented a new and useful Improvement in Printing Mechanism, of which the following is a specification.

This invention relates to gearing for rotary printing machines and has for its object to so arrange the plate cylinder that it will be permitted a limited rotary movement with respect to its gear whereby the movement of the plate cylinder during the printing operation will be under the control of the plate; novel means being employed for automatically bringing the plate cylinder into proper register with the impression cylinder at a predetermined portion of the rotary movement of said cylinder and locking the cylinder in such proper register to its gear after the completion of the printing operation, preferably at the beginning of said printing operation, said cylinder being immediately released to permit the printing operation to be continued without being influenced by its gear connection with the impression cylinder.

In the accompanying drawings, I have shown the invention as applied to a multi-color rotary printing machine.

Figure 1 represents in partial side elevation so much of a four-color rotary printing machine as will give a clear understanding of my invention. Fig. 2 is a partial end view of the same, Fig. 3 is a detail section showing the parts in the position which they assume when the plate cylinder is locked to its gear at the beginning of the printing operation, and Fig. 4 is a similar view with the parts in the position which they assume when the plate cylinder is released from its gear and has traveled 180° from the position shown in Fig. 3.

The side framing of the machine is denoted by 1. The impression cylinder by 2 and each of the plate cylinders by 3. The impression cylinder gear is denoted by 4, which gear may be driven from a gear 5 on the driving shaft 6. The plate cylinder gears driven from the impression cylinder gear 4 are denoted by 7 and their stationary controlling cams by 8, which cams are herein shown as carried by the side framing 1,

As the control of all of the plate cylinders 55 is the same, I will proceed to describe in detail the construction, form and operation of the means for controlling one only of said plate cylinders.

The semi-circular groove in the cam 8 60 is eccentric to the axis of the plate cylinder 3 and gear 7 and the outermost point of said cam groove is so situated as to lock the plate cylinder to its gear at the beginning of the printing operation.

A cam lever 9 is pivoted at 10 to the plate cylinder 3, which lever is provided with a cam roller 11 arranged to pass through the stationary cam 8 during the rotation of said plate cylinder.

Means are provided for bringing the plate cylinder into proper register and for locking the plate cylinder to and releasing it from its gear, which means may comprise a wedge 12 on the cam lever 9, arranged to 75 be brought into and out of locking engagement with seats 13, 14, formed, in the present instance, by blocks secured to the plate cylinder gear 7, said wedge being so arranged that when the cam roller 11 on the 80 cam lever 9 is moved outwardly by the cam 8 the cylinder 3 will be locked to the gear 7 and when moved inwardly the cylinder will be permitted a limited rotary movement with respect to its gear.

The bolts 15 which secure the gear 7 to the end of the plate cylinder pass through enlarged holes 16 in the gear so as to permit this limited rotary movement of the cylinder in either direction while the gear is 90 held close to the end of the cylinder.

A spring device 17 carried by the cylinder serves to normally swing the cam lever 9 and its roller inwardly.

In operation: presupposing the parts to 95 be in the position shown in Fig. 3, with the plate cylinder locked to its gear, the form on the plate cylinder being in position to start the printing operation: As soon as the printing operation has begun, the cam 8 will, 100 because of its engagement with the roller 11, rock the lever 9 inwardly thus withdrawing the wedge 12 out of contact with its seats 13, 14, thus leaving the cylinder 3 free to move rotatively to a limited extent with respect to its gear 7. The travel of the plate cylinder is then controlled entirely by the form thereon without being influenced by 105

the gear connection between the impression and plate cylinders. After the printing operation has been completed, the continued rotary movement of the plate cylinder will cause the stationary cam 8, because of its engagement with the roller 11, to move the lever 9 outwardly against the tension of its spring device 17 and bring the wedge 12 into locking engagement with the seats 13, 14. This movement will, at every revolution of the plate cylinder, bring it into absolute register with its impression cylinder just before the next succeeding printing operation is started. It will thus be seen that the plate and impression cylinders must always be brought into the same relative positions before each successive printing operation, the printing operation itself being carried on while the plate cylinder is free to move independent of the geared connection with the impression cylinder and by the frictional contact of its form with the impression cylinder.

The releasing of the plate cylinder gear to permit the plate cylinder a limited free movement in either direction, gives the pressman a great deal more latitude for "making ready" the form than where this is not done. If the form is high, the tendency is for the plate cylinder to drop back slightly during the printing operation. If the form is low, the plate cylinder will run slightly ahead during the printing operation. This loss or gain in the travel of the plate cylinder is corrected for the next successive printing operation by bringing the cylinder into register and locking the cylinder to its driving gear as hereinabove set forth. As the travel of the plate cylinder is controlled entirely by the form during the printing operation, a slight variation

in the height of the plates and backing does not destroy any of the plate values.

It is evident that slight changes might be resorted to in the form, construction and arrangement of the several parts without departing from the spirit and scope of my invention; hence I do not wish to limit myself strictly to the structure herein set forth, but

What I claim is:—

1. Printing mechanism including a gear, a plate cylinder having a limited rotary movement with respect thereto, a stationary cam, a rocking lever carried by the cylinder and a wedge on the rocking lever moved by said cam into engagement with the gear for bringing the cylinder into register therewith.

2. Printing mechanism including a gear, a plate cylinder having a limited rotary movement with respect thereto, a stationary cam, seats on the gear, a rocking lever carried by the cylinder and a wedge on the rocking lever moved by said cam into locking position between said seats for bringing the cylinder into register with said gear.

3. Printing mechanism including a gear, a plate cylinder, means for securing the gear to the cylinder with a limited rotative lost motion, a stationary cam and means carried by the cylinder moved by said cam into engagement with the gear for bringing the cylinder into register therewith.

In testimony, that I claim the foregoing as my invention, I have signed my name in presence of two witnesses, this twenty third day of June, A. D. 1911.

CHARLES P. COTTRELL.
